(57) **CLAIM**

The ornamental design for a tape dispenser, as shown and described.

DESCRIPTION

In the drawings which show a dispenser for tape-like material like correction or adhesive tape, having a transparent casing with a non-transparent slide cover protruding from the casing, which can be slidably moved between retracted and advanced positions for covering or exposing a non-transparent application head held by the casing.

FIG. 1 is a front view with the slide cover in the retracted position for exposing the application head,

FIG. 2 is a rear view,

FIG. 3 is a right side view,

FIG. 4 is a left side view,

FIG. 5 is a top view,

FIG. 6 is a bottom view,

FIG. 7 is a perspective view with the slide cover in the retracted position for exposing the application head; and,

FIG. 8 is a perspective view with the slide cover in the advanced position for covering the application head.
